UNITED STATES PATENT OFFICE.

WILLIAM L. DEMING, OF SALEM, OHIO.

GARMENT-SUPPORTER.

1,152,492.

Specification of Letters Patent. Patented Sept. 7, 1915.

Application filed September 13, 1913. Serial No. 789,583.

To all whom it may concern:

Be it known that I, WILLIAM L. DEMING, a citizen of the United States, residing at Salem, in the county of Columbiana and State of Ohio, have invented a certain new and useful Improvement in Garment-Supporters, of which the following is a full, clear, and exact description, reference being had to the accompanying drawings.

10 This invention relates to devices for temporarily fastening one garment to another; for example, attaching the stocking to underwear to support the stocking and hold down the underwear.

15 The invention consists of a clamp made of a single piece of metal bent on itself into peculiar form and adapted to grip the two fabrics which it is desired to hold together. The peculiar form into which the device is bent allows it to be easily put in place and easily removed, but, when it is in place, it effectively holds the fabrics together.

20 The invention is hereinafter more fully described in connection with the drawings 25 hereof.

In the drawings, Figure 1 is a view of my holding clip; Fig. 2 is a view showing the same in place holding a stocking on to underwear; Fig. 3 is a vertical section on an 30 enlarged scale through the clip and the gripped fabrics shown in Fig. 2.

Referring to Fig. 1, my clip will be seen to consist of a single piece of bent metal, preferably round wire. Such wire is bent 35 on itself to produce a concave intermediate or head portion 1, two rounded shoulders 2 at the ends of the intermediate portion, then inwardly projecting portions 3, and then longitudinal portions 4 which extend from 40 the portions 3 at an angle thereto and preferably diverging slightly. At the ends of the portion 4 are rounded returned ends 5 which lead to the tines 6, which are shown as parallel to each other and normally con- 45 tact, or approximate contact. At their inner ends, these tines 6 are bent outwardly, as shown at 7, these bent portions projecting approximately toward the shoulders 2. These ends are bent outwardly and their 50 extremities rounded to prevent the fabric being caught between or on the ends and torn or worn. The intermediate portion 1 is bent inwardly, that is, toward the ends 7, 7, for purposes hereinafter explained.

55 In Figs. 2 and 3, A indicates the under- wear and B the stocking. In putting the

clip in place, a doubled portion of the stocking and underwear is pinched together with the fingers into a loop, as shown at C in Fig. 3, and then the clip is shoved onto 60 such doubled portion so that the tines 6 lie on opposite sides thereof, and, by the resiliency of the clip, clamp such parts together. In this shoving action, the rounded portion of the clip where the return bends 5 join, 65 the tines 6 form a flaring mouth enabling the device to be put easily in place. It is shoved into place by pressure on the intermediate concave portion 1, the concavity of this portion centering the operator's thumb 70 on it and allowing it to be easily shoved home. In this movement, the converging shoulders 3 allow the clip to be grasped at the same time by the operator's first and second finger, so that the clip may be conveniently picked up and inserted by one hand while the other hand holds the pinched 75 fabric.

When the supporter is in position the parallel members 6 embrace a looped rib formed 80 in the hose and underwear. This looped rib is spread by the curved intermediate portion of the supporter 1, substantially into a Y, thereby bringing a portion of the hose and underwear opposite each of the ends 7, the 85 fabric extending into the space beyond those ends. This normally prevents inadvertent removal of the supporter, but the ends 7 being rounded and flared apart as shown, 90 may be pulled over these raised portions without danger of catching in or tearing the garments, when it is desired to remove the supporter. Accordingly my clip effectively binds the stocking and underwear, or other 95 garments which are secured by it.

The device is small and lies close to the garment, so that it is out of the way and un- 100 observable. To remove it, it is simply pulled backwardly, the inwardly bent portions 3 of the clip forming grips for two 105 fingers to pull the clip out of place, and the flared ends 7 sliding easily over the folded or raised portions of the stocking. The clip is thus operated in either direction by the thumb bearing against the bent portion 1 and the first and second fingers against the shoulders 3.

Having thus described my invention, what I claim is:

A garment fastener made of a single piece 110 of spring-metal bent on itself to provide the following parts, namely: an inwardly bent

intermediate portion, two rounded shoulders adjacent thereto, two inwardly bent portions leading from the respective rounded shoulders, two longitudinal portions leading away from the inwardly bent portions, two return bends leading from the ends of the longitudinal portions, two adjacent tines leading from these bends toward said shoulders and between the longitudinal members 10 and having their free ends flared apart and

terminating within the space provided by the inwardly bent portions and the intermediate portion, as described.

In testimony whereof, I hereunto affix my signature in the presence of two witnesses. 15

WILLIAM L. DEMING.
